PRESSER FOOT FOR SEWING MACHINES

Charles A. Kessler, Plainfield, N. J., assignor to
The Singer Manufacturing Company, Elizabeth, N. J., a corporation of New Jersey

Application November 30, 1943, Serial No. 512,376

6 Claims. (Cl. 112—235)

This invention relates to sewing machine presser-feet and more particularly to a presser-foot which is particularly adapted for stitching work having heavy cross-seams therein.

Heretofore difficulty has been experienced when the conventional presser-foot, having a pivotal sole-portion, has been used in combination with a four-motion feed-dog in stitching work having heavy or thick cross-seams. This difficulty arose due to the fact that the toe-portion of the foot would not readily rise and ride over the heavy cross-seams, and as a result the speed of the work past the needle was reduced, thereby causing a decrease in the length of the stitches in the region of a cross seam.

It is the object of this invention to provide a presser-foot that will tilt and ride over the cross-seam without retarding the movement of the material through the machine.

With the above and other objects in view, as will hereinafter appear, the invention comprises the devices, combinations and arrangements of parts hereinafter set forth and illustrated in the accompanying drawing of a preferred embodiment of the invention, from which the several features of the invention and the advantages attained thereby will be readily understood by those skilled in the art.

In the drawing:

Fig. 1 is an end elevation of the stitch-forming and feeding mechanism of a sewing machine showing my improved presser-foot.

Fig. 2 is a side view of the presser-foot, showing the position of the parts of the foot when a cross-seam is encountered.

Fig. 3 is a top plan view of the presser-foot.

Fig. 4 is a perspective view of the stop spring used with the presser-foot.

In the embodiment of the invention selected for illustration my improved presser-foot is shown applied to a sewing machine having a bed 10 and head 11. Journaled below the bed 10 is a rotary hook 12 and the usual feed rock-shafts 13 and 14 which impart a four motion movement to a feed-dog 15, in the usual and well known manner.

Journalized for reciprocatory movement in the head 11 is a needle-bar 16 carrying an eye pointed needle 17. Also journalized for a right line up and down movement in the head 11 is the usual spring depressed presser-bar 18. For a complete and detailed description of the sewing machine mechanism reference may be had to the patent to Kaier No. 2,206,285, dated July 2, 1940.

Removably secured to the lower end of the 55

presser-bar 18 by means of a screw 19 is a presser-foot comprising a shank 20 having a forwardly extending portion 21. A sole-plate 22 having upstanding ears 23, which are located on the opposite side of the forwardly extending portion 21, are secured thereto by a pivot pin 24. The sole-plate 22 is formed with an upwardly curved heel portion 25 and a bifurcated toe-portion providing two forwardly extending portions 27, 28 with a space therebetween through which the needle 17 descends. Located in rear of the pivot pin 24, with one end disposed in a recess in the portion 21 of the shank, is a compression spring 29 which reacts between the portion 21 and the heel of the sole-plate to constantly urge the heel 25 downwardly and, as viewed in Fig. 1, the sole-plate in a counter-clockwise direction about the pivot 24. This construction causes the toe of the sole-plate to be inclined upwardly and at an angle to the throat-plate 30 when the presser-bar is raised, thereby facilitating the insertion of a new piece of material under the sole-plate preparatory to sewing.

It has been found that when a conventional presser-foot of the above described type is used in stitching work having heavy or thick cross-seams the toe-portion of the sole-plate would not readily rise and ride over the seam. To overcome this difficulty the length of the toe-portion of the sole-plate was increased and the length of the heel portion decreased to provide a more advantageous lever action when the seam engages the toe-portion. When the necessary advantage in leverage is thus obtained the toe-portion, due to the reduced heel length, will rise so high that the cross-seam will jam against the sharply inclined sole-plate thereby reducing the feeding effect of the feed-dog and resulting in stopping of the feeding of the work or reducing the length of the stitches.

To apply pressure on the toe of the sole-plate and to limit the tilting movement of the sole-plate to prevent it from rising too high and thus reducing the feeding effect of the feed-dog, I have provided a flat U-shaped spring 31 which is spaced above the sole-plate 22 as shown in Fig. 1. The spring is formed with a laterally extending L-shaped portion 32, which together with the upper end of the spring forms a trough-shaped portion which is adapted to embrace the upper end of the shank 20. The L-shaped portion 32 is formed with a slot 33 which is adapted to receive the screw 19, thereby providing means for varying the height of the spring 31 above the sole-plate 22.

As shown in the drawing the free end of the spring 31 extends outwardly to a point adjacent the end of the toe-portion 28 so that when the cross-seam C (Fig. 2) is encountered the toe of the sole-plate will rise until its end strikes the end of the spring 31. The angle at which the sole-plate may be tilted is limited by the spring and, therefore, cannot be tilted at an angle great enough to form an obstruction to the passage of the seam. After the sole-plate has reached the position shown in Fig. 2 the feed-dog 15 advances the material and the presser-foot rises and rides over the seam without hinderance.

It is of course understood that the embodiment above described, and shown in the drawing, is illustrative of my invention and is not employed by way of limitation, inasmuch as numerous changes and modifications may be made within the scope of the appended claims without departing from the spirit of my invention.

Having thus set forth the nature of the invention what I claim herein is:

1. A sewing machine having in combination, a presser-foot comprising a shank and a sole-plate pivotally secured to the lower end thereof, said sole-plate being formed with a forwardly extending toe-portion, and a flat U-shaped spring having one end secured to said shank and spaced above said sole-plate, said spring extending outwardly over the sole-plate and having its free end overlying and spaced above said toe-portion.
2. A sewing machine presser-foot comprising a shank adapted for attachment to the presser-bar of a sewing machine, said shank having a depending portion to which a sole-plate is pivotally secured, a flat spring having one end adjustably secured to said presser-foot and its free end overlying and spaced above said sole-plate.
3. A sewing machine attachment for use with

a sewing machine equipped with a presser-foot having a sole-plate adapted for movement about a horizontally arranged pivot comprising a spring overlying and spaced above said sole-plate, one end of said spring being adjustably secured to said presser-foot for vertical adjustment whereby the distance between the free end of said spring and the sole-plate may be varied.

4. In combination, a sewing machine presser-foot having a shank adapted to be secured to the presser-bar of a sewing machine by a screw, a sole-plate pivotally secured to said shank for tilting movement about a horizontal axis, said sole-plate having a heel and toe-portion, and a flat spring having one of its ends embracing said shank and clamped thereto by said screw, and its free end spaced above and overlying the toe-portion of said sole-plate.

5. A sewing machine having in combination, feeding mechanism including a four motion feed-dog, a presser-foot having a hinged sole-plate cooperating with said feed-dog to advance the work and having a heel and toe-portion and a U-shaped spring having one of its ends overlying said sole-plate and spaced above the toe-portion thereof in a position to be engaged by said toe-portion when a cross-seam is encountered.

6. An attachment for a sewing machine presser-foot having a pivoted sole-plate formed with a toe-portion comprising a flat U-shaped spring having at one end thereof a trough shaped shank adapted to embrace the shank of a sewing machine presser-foot, said trough shaped shank of the spring being formed with a slot in one of its walls and the other end of the spring being spaced from and adapted to overlie the toe-portion of the sole-plate in the normal position of the latter.

CHARLES A. KESSLER.
